Fig. 3

Fig. 4

Fig. 5

FIGURE 1 is a front perspective view of the test instrument embodying our new design.

FIGURE 2 is a bottom view;

FIGURE 3 is a top view;

FIGURE 4 is a left end elevational view; and

FIGURE 5 is a rear elevational view thereof.

The characteristic feature of my design for a test instrument resides in the specific appearance of the meter face in combination with the casing as shown.

We claim:

The ornamental design for a test instrument substantially, as shown and described.
